STRAND GUIDING AND TENSIONING DEVICE

Arthur Kuettiler, Jr., Berwyn, and Fred Radakovich, Chicago, Ill., assignors to Western Electric Company, Incorporated, New York, N. Y., a corporation of New York

Application October 5, 1949, Serial No. 119,586

6 Claims. (Cl. 242—151)

1

This invention relates to a strand tensioning device and more particularly to a rotary device for tensioning wire for use in a coil winding machine.

It is an object of the present invention to provide an improved adjustable rotary device for applying a variable tension to a moving strand.

In one embodiment of the invention, a pair of resilient rollers are mounted in spaced relation to each other for engagement at spaced points with the periphery of a metal roller to frictionally and rotatably engage a wire disposed therebetween. The resilient rollers are mounted on the ends of a pressure equalizing lever pivoted intermediate its ends and the metal roller is mounted for movement toward and away from the resilient rollers to permit the threading of the strand between the rollers, and an adjustable locking mechanism holds the metal roller in adjusted position and is operable to vary the pressure between the resilient rollers and the metal roller to apply a selectively variable tension to the moving strand disposed therebetween.

In another embodiment of the invention, a strand is guided between and gripped at spaced points by a pair of spaced-apart resilient rollers mounted on fixed axes and a movable metal roller mounted for movement toward and away from said resilient rollers and supported for free movement transversely to the direction of said first movement to permit the equalization of pressure between said metal roller and the resilient rollers. Adjusting means serves to vary the pressure between the metal roller and the resilient rollers to apply a variable tension to the moving strand disposed between said metal and resilient rollers.

In still another embodiment of the invention, the strand is passed between a resilient and a nonresilient roller, one of which is mounted for movement relative to the other and has adjustable means for moving it into engagement with the other roller to frictionally and rollingly engage a strand passing therebetween and for applying a variable tension to said moving strand.

Other objects and features of the invention will become apparent by reference to the following description and the accompanying drawings illustrating several embodiments thereof in which

Fig. 1 is a somewhat diagrammatic vertical sectional elevational view of a coil winding machine showing the strand guide and tensioning device in position therein;

Fig. 2 is an enlarged detail face view of the strand guide and tensioning device;

2

Fig. 3 is a fragmentary view of the device similar to Fig. 2 showing parts of the tensioning device in open position to permit the insertion of a strand therein;

Figs. 4 and 5 are vertical sectional views taken on the line 4—4 and 5—5, respectively, of Fig. 2;

Fig. 6 is a plan sectional view taken on the line 6—6 of Fig. 2; and

Figs. 7 and 8 are elevational views similar to Fig. 3 illustrating modified forms of construction of the invention.

Referring to the drawings, particularly Fig. 1, the strand guide and tensioning device 10 is shown in connection with a coil winding machine 12 having a rotatable mandrel 14 about which alternate layers of a strand 16 and strips of paper 18 are wound to form a coil. The strand 16 is unwound from a reel 20 and passes through a guide member 21 into the tensioning device 10. Mounted on a reciprocable distributing rod 24, the wire guide and tensioning device 10 is reciprocated axially of the mandrel 14 in timed relation with the rotation of the mandrel.

The wire guide and tensioning device 10 comprises a vertically disposed main supporting plate 25, on which are mounted, for limited movement, a pair of resilient rollers 27 and 28 and a nonresilient roller 30. The tensioning rollers 27, 28 and 30 have cylindrical peripheral surfaces and the roller 30 is mounted for movement into and out of peripheral engagement with the resilient rollers 27 and 28 to facilitate the threading of a strand 16 into operative engagement with the rollers and also to adjust the pressure between the roller 30 and the resilient rollers 27 and 28.

To equalize the pressure between the roller 30 and the resilient rollers 27 and 28, the resilient rollers 27 and 28 are mounted on the ends of a pressure equalizing member 31 which is pivotally supported intermediate its ends on a pivot stud 32 fixed to the plate 25. The member 31 preferably is in the form of a bell crank with the pivot 32 located at the elbow thereof. Made from any suitable resilient or yieldable material, such as rubber, the rollers 27 and 28 are each provided with an annular metal insert 35 having a concentric bore into which may be pressed an Oilite bearing bushing 36 having cylindrical bearing surfaces concentric with the periphery of the roller. The rollers 27 and 28 are rotatably mounted on cylindrical bearing pins 38 secured to the ends of the pressure equalizing bell crank lever 31 and the rollers are retained on the bearing pins 38 by split retaining washers 40 engageable in grooves in the bearing pins.

The nonresilient roller 30 is preferably made

from metal and has a bore for receiving a bearing bushing 48 which has a cylindrical bearing surface concentric with the periphery of the roller. A cylindrical bearing member 50 rotatably supports the roller 30 and is fixed to one end 52 of a cross arm of a substantially T-shaped supporting bracket 54 and is grooved for receiving a retaining washer 55 for retaining the roller 30 thereon. The supporting bracket 54, at its lower end, is pivotally supported for limited pivotal movement on a stud 57 secured to the plate 25 and is provided with a shoulder 58 engageable with a pin 59 on the plate 25 for limiting the swinging movement of the supporting bracket 54 and the roller 30 in one direction.

Extending from the other arm 60 of the T-shaped supporting member 54 is a pin or stud 61, which is engageable with the end of an adjustable set screw 62 threadedly mounted in the end 63 of a latch member 64 and held in adjusted position therein by a lock nut 68. The latch member 64 is pivotally attached to the supporting plate 25 for swinging movement about the pivot stud 32. In the lower or normal operative position of the latching member 64, in which position it is supported by a stop pin 68 on the plate 25, the set screw 62 is positioned slightly below dead center of the stud 61 to lock the latch 64 in position and serves to move the supporting bracket 54 to the right, Fig. 2, and to hold the roller 30 in engagement with the resilient rollers 27 and 28. The latch 64 may be swung upwardly to an inoperative position, as indicated in Fig. 3, to permit the roller 30 and the supporting bracket 54 to be moved to an open position, also indicated in Fig. 3, to facilitate the threading of a strand into operative position with the tensioning rollers. The strand is guided for movement in a plane parallel to the face of the supporting plate 25 and in alignment with the tensioning rollers by suitable guide means including upper and lower guides 72 and 74, respectively. Each of the guides 72 and 74 comprises a pair of spaced substantially flat sheet metal members secured to the plate 25 in laterally spaced relation to each other to receive the wire therebetween. The strand 16, as it leaves the tensioning rollers 27 and 28, passes around a grooved idler roller 76 rotatably mounted on the supporting plate 25. As the strand continues, it passes around a portion of the flanged idler guide roller 78 mounted for rotation on the supporting plate 25.

It will be seen that in the embodiment just described the strand engages a substantial periphery of the metal tensioning roller 30 and is pressed into engagement therewith at spaced points by the resilient tensioning rollers 27 and 28 and has a tension or drag applied thereto created by the frictional resistance of the rollers on their respective bearing members. By adjusting the set screw 62, the pressure between the roller 30 and the resilient rollers 27 and 28 may be varied to vary the frictional resistance between the bearings and their respective rollers and thus permit the application of a selectively variable tension to the strand.

The structure of the embodiment illustrated in Fig. 7 is similar to that illustrated in Figs. 2 to 6 except that the resilient rollers 127 and 128, corresponding to rollers 27 and 28, are mounted for rotation about bearing members 129-129 mounted in fixed position on the main supporting plate 125. A metal roller 130, similar to the roller 30, is mounted for rotation on a cylindrical

bearing 131, fixed to one end of a supporting arm 132. The supporting arm 132 has a pivotal connection 161 to an oscillatable supporting lever 154 mounted for limited swinging movement about the pivot 157. The roller 130 and the supporting arm 132 have a restricted rocking movement about the pivotal connection 161, limited by stop lugs 158-158 formed on the supporting member 154. The pivotal connection 161 has an outwardly extending stud formed thereon similar to the stud 61, and a set screw 162 adjustably mounted in an oscillatable latch 164 engages the stud 161 and serves to hold the roller 130 in engagement with the rollers 127 and 128. In this construction, the roller 130 is freely movable in a vertical direction so that, as it is moved into compressive engagement with the rollers 127 and 128, it is free to adjust its position and equalize the pressure between itself and the resilient rollers and thereby cause the strand to be gripped with equal pressure between the roller 130 and the rollers 127 and 128.

In the construction of the embodiment illustrated in Fig. 8, the strand is engaged between a pair of tensioning rollers, one of which is resilient and one of which is mounted for movement relative to the other to selectively vary the tension applied to the strand. A yieldable roller 227 is mounted for rotation about a cylindrical bearing 229 mounted in fixed position on a supporting plate 225. The other roller 230 of the pair of tensioning rolls is mounted for rotation about a cylindrical bearing member 231, which is fixedly mounted on a supporting bracket 254. The supporting arm 254, which is identical with the supporting arm 54, is mounted for limited oscillating movement about a pivot 257 and an adjustable set screw 252, carried by an oscillatable latch member 264 similar to latch 64, engages a stud 261 on the supporting arm 254 to hold the roller 230 in engagement with the roller 227. The set screw 252 may be adjusted to control the pressure between the rollers 227 and 230 to selectively vary the tension applied to the strand passing between the rollers.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A strand tensioning device comprising a supporting plate, a pair of resilient rollers having strand engaging peripheries, a pressure equalizing member, means mounting said resilient rollers for rotation on said member about parallel axes and in predetermined spaced relation to each other, means mounting said member for pivotal movement on said plate about an axis intermediate said rollers, a nonresilient roller having a strand engaging periphery, means including an oscillatable supporting member pivotally mounted on said plate for rotatably supporting said nonresilient roller and for guiding said roller for movement into and out of peripheral engagement with said resilient rollers, and a latch member pivotally mounted on said plate and having an adjustable locking member thereon engageable with said supporting member for holding said nonresilient roller in engagement with said resilient rollers and for adjusting the pressure therebetween.

2. A strand tensioning device comprising a

supporting plate, an arm pivotally mounted intermediate its ends on said plate, a pair of resilient rollers having strand engaging peripheries and rotatably mounted on the ends of said arm in spaced relation to each other, a non-resilient roller having a strand engaging periphery engageable at spaced points thereon with the peripheries of said resilient rollers for gripping a strand disposed therebetween, movable supporting means on said plate for supporting said nonresilient roller for rotation and for guiding said roller into and out of engagement with said resilient rollers, and adjustable means engageable with said supporting means for holding said nonresilient roller in engagement with said resilient rollers, and for adjusting the pressure between the nonresilient and resilient rollers.

3. A strand tensioning device comprising a supporting member, an arm pivotally mounted intermediate its end on said member, a pair of resilient rollers having strand engaging peripheries mounted on the ends of said arm in spaced relation to each other, a non-resilient roller, a second arm pivotally mounted on said supporting member and rotatably supporting said non-resilient roller for oscillating movement through a predetermined path to and from an open position in spaced relation to said resilient rollers and a closed position in engagement with said resilient rollers for gripping a strand disposed therebetween, a latch member mounted on said supporting member having an element engageable with said second arm in its closed position for holding said non-resilient roller in engagement with said resilient rollers, and means for adjusting said element on said latch member to vary the pressure between said rollers.

4. A device for applying a tension to a moving strand comprising a pair of rollers having strand engaging peripheries, a member supporting said rollers for rotation in predetermined fixed spaced relation to each other, a third roller having a strand engaging periphery engageable at spaced points thereon with the peripheries of said pair of rollers, supporting means mounting said third roller for movement into a closed position in engagement with said pair of rollers and an open position in spaced relation to said pair of rollers, adjacent rollers alternately having hard and resilient peripheries to provide cooperating hard and soft gripping surfaces on adjacent rollers for gripping said strand therebetween, said supporting means comprising an element mounted on said member for movement in a predetermined path toward and away from said rollers and a second element rotatably supporting said third roller and pivotally mounted on said first element in spaced relation to said third roller for guiding said roller for free floating movement transversely to the movement of said first element to permit the equalization of pressure between said third roller and said pair of rollers during the rotation of the rollers and the movement

of the strand therebetween, and adjustable means cooperating with said supporting means for locking said third roller in engagement with said pair of rollers under various pressures.

5. A device for tensioning a moving strand comprising a pair of rollers having strand engaging peripheries, means for supporting said rollers for rotation about parallel axes in a predetermined fixed spaced relation to each other, a third roller having a strand engaging periphery engageable at spaced points thereon with the periphery of said pair of rollers, a first arm for rotatably supporting said third roller thereon, a second arm for pivotally supporting said first arm thereon for movement about a first axis spaced from said third roller, means supporting said second arm on said supporting means for pivotal movement about a second axis in spaced relation to said first axis, said parts being arranged to permit movement of said second arm and the first arm and roller carried thereby in one direction toward and away from said pair of rollers to move said third roller into and out of engagement with said pair of rollers and to permit free pivotal movement of said first arm and the roller thereon transversely to said one direction to effect the equalization of pressure between said third roller and said pair of rollers during the rotation of the rollers and the movement of the strand therebetween, and latch means having an adjustable element engageable with said second arm for locking said third roller in engagement with said pair of rollers under various pressures.
6. A strand tensioning device comprising a supporting member, an arm pivotally mounted intermediate its ends on said member, a pair of rollers having strand engaging peripheries mounted on the ends of said arm in spaced relation to each other, a third roller, an element mounted on said supporting member for movement through a predetermined path and for rotatably supporting said third roller for movement to and from an open position in spaced relation to said pair of rollers and a closed position in engagement with said pair of rollers for gripping a strand disposed therebetween, and means engageable with said element for holding said third roller in engagement with said pair of rollers under various pressures.
